United States Patent Office

Des. 221,301
Patented July 27, 1971

221,301

MACHINING CENTER

Brooks Stevens, Fox Point, Wis., assignor to Kearney & Trecker Corporation, West Allis, Wis.

Filed Apr. 27, 1970, Ser. No. 22,652

Term of patent 14 years

Int. Cl. D15—05

U.S. Cl. D54—14

FIG. 1.

FIG. 2.

FIG. 3.

FIG. 4.

FIG. 5.

FIG. 1 is a perspective view of a machining center showing the front and right side thereof illustrating my new design;

FIG. 2 is a front view in elevation of the machining center;

FIG. 3 is a right side view in elevation of the machining center;

FIG. 4 is a left side view in elevation of the machining center; and,

FIG. 5 is a top plan view of the machining center. The rear side, not shown, of the machining center being substantially plain.

I claim:

The ornamental design for a machining center, substantially as shown and described.
